TOOLHOLDER

John F. Golden, Lynn, and Harold J. Smith,
Everett, Mass.

Application May 3, 1945, Serial No. 591,767

1 Claim. (Cl. 82—12)

(Granted under the act of March 3, 1883, as
amended April 30, 1928; 370 O. G. 757)

1

Our invention relates to a toolholder. It has to do, more particularly, with a toolholding attachment for use on machine tools and which is especially suitable for turning out curved surfaces on the work.

At present, attachments are provided on machine tools such as lathes for turning out work with curved surfaces, for example, spherical surfaces. However, with present devices it is difficult to change the position of the tool post each time it is desired to change the radius of the surface to be produced. It is necessary to use a wrench or other tool to release the clamp on the tool post, slide the post along a guide to its new position, and then use the wrench to again clamp the tool post in position. It is also difficult to locate the tool post accurately.

One of the objects of our invention is to provide a toolholder which is of such a nature that it may be easily and quickly actuated to position the toolholder properly to turn out curved surfaces of a pre-selected radius.

Another object of our invention is to provide a toolholder which is of simple structure but which can be actuated to accurately position the tool as desired.

The preferred embodiment of our invention is illustrated in the accompanying drawings wherein similar characters of reference designate corresponding parts and wherein:

Fig. 1 is a side elevational view of a lathe with our toolholder positioned thereon.

Fig. 2 is a perspective view of our toolholder.

Fig. 3 is a top plan view, partly broken away, of our toolholder.

Fig. 4 is a view of our toolholder, partly in side elevation, but mainly in vertical section along line 4—4 of Fig. 3.

With reference to the drawings, in Fig. 1 we have illustrated a lathe 1 to which our toolholder 2 is shown attached. The toolholder is carried on the carriage 3 of the lathe by being attached directly to the compound rest 4 thereof.

Our toolholder comprises a supporting plate 5, as shown in Figs. 2, 3, and 4, which has an integral support 6 at its rear edge. The support 6 extends upwardly and includes a rearwardly extending horizontally disposed arm 7. This arm 7 is of square cross-section. The arm 7 is clamped to the compound 4. This is accomplished with a clamp 8 (Fig. 1) which has a T-bolt 9 fitting into the undercut slot in compound 4 and a bar 10 which engages the top of arm 7.

The plate 5 carries on its upper surface a swing-arm 11. This arm 11 is in the form of a

2

block which has a guideway 12 (Figs. 3 and 4) formed in its lower surface and extending longitudinally thereof. This guideway 12 is in the form of a T-slot and has a T-shape guide 13 disposed therein. The guide 13 is formed on the upper end of a vertically-disposed pivot pin 14 which is rotatably disposed in a vertical opening 15 formed substantially at the center of plate 5.

The guideway 12 has a screw 16 extending longitudinally thereof. This screw is threaded through the guide 13 and its outer end is rotatably disposed in a bearing member 17 at the outer end of the guideway. The screw 16 is provided with a square outer end 18 for receiving a crank 19 by which it may be rotated. Rotating screw 16 will move the arm 11 radially on plate 5 relative to pin 14.

The arm 11 carries adjacent to its outer end a tool post 19. This tool post has a flanged lower end 20 disposed within the arm 11. A sleeve 21 surrounds the post and rests on the upper surface of arm 11. The post 19 has a vertical slot 22 formed therein and extending below the upper edge of sleeve 21. This slot receives a cutting tool 23 which is clamped therein by a screw 24 threaded through the top of the post.

The pin 14 extends through plate 5 and has a horizontally-disposed worm gear 25 keyed on its lower end. The gear 25 is held in its horizontal position by a nut 26 threaded on the lower end of pin 14 and engaging the lower surface of the gear 25. A worm 27 meshes with the gear 25. This worm 27 is carried by a horizontally disposed shaft 28 which extends transversely of plate 5 and is rotatably carried in bearings 29 and 30 carried by the plate 5. The lower surface of plate 5 is recessed to receive the bearings 29 and 30 and the worm 27, as shown in Figs. 3 and 4. A housing 31 is secured below the plate 5 for enclosing the worm and gear mechanism. The shaft 28 extends from the housing 31 and its outer end has a handwheel 32 keyed thereon by means of which it may be rotated.

In using our attachment, the work is placed in a chuck 33 mounted on the spindle of the lathe. The work, in the example shown, is in the form of a cylinder 34 of metal which is to have a spherical socket formed therein. The cutting tool 23 is so positioned that a surface of predetermined radius will be cut on the work. This adjustment is easily and quickly made by operating the screw 16 to move the tool post 19 relative to the pin 14, about which the arm 11 will swing. To cut the spherical surface on the work, the carriage 3 is adjusted until the tool contacts with the work

34. The handwheel 32 is then operated to cause the cutting tool 23 to swing across the face of the work. Since the arm 11 swings about pivot pin 14 and since the work 34 is rotating, the desired concave spherical surface will be produced on the work. The radius of curvature of the surface produced may be changed readily and accurately by operation of the screw 16 to move arm 11 radially.

Our attachment is particularly suitable for use 10 on lathes and boring mills but is capable of application to other machine tools such as shapers and planers, for example, for cutting curved surfaces.

The invention described herein may be manufactured and used by or for the Government of the United States of America for governmental purposes without the payment of any royalty thereon or therefor.

Having thus described our invention, what we 20 claim is:

A tool holding attachment of the type described comprising, a supporting plate, a support at the rear edge of and integral with said supporting plate, said support extending upwardly from said supporting plate and including a rearwardly extending horizontal arm, said arm providing means by which said attachment may be supported, a swinging block adapted to be carried on the upper surface of said supporting plate, 30 said swinging block having a T-shape guideway formed in its lower surface and extending longitudinally thereof, a vertically disposed pivot pin, said pivot pin adapted to be rotatably mounted through and substantially at the center of said 35 supporting plate, a T-shape guide formed on the upper end of said pivot pin and adapted to be disposed in said T-shape guideway in said swing-

ing block, a screw extending longitudinally of said T-shape guideway, said screw threaded through said T-shape guide and rotatably mounted in the end of said swinging block, means for rotating said screw, said rotation imparting radial movement to said swinging block with respect to said pivot pin, a tool post mounted vertically at the outer end of said swinging block, said post having a vertical slot therein, a sleeve about the outside of said post, a screw threaded in the top permitting the insertion and clamping of a cutting tool in said vertical slot against said sleeve, a gear located at the lower end of said pivot pin and keyed to said pivot pin, a shaft extending transversely of said supporting plate, a worm located on said shaft, said worm meshing with said gear, and a handwheel to turn said shaft causing said swinging block to be rotated about said pivot pin.

JOHN F. GOLDEN.
HAROLD J. SMITH.
